N. T. Greene,

Steam Cut-Off

N° 12,507.

Patented Mar. 13, 1855.

Inventor

UNITED STATES PATENT OFFICE.

NOBLE T. GREENE, OF BRIDGEPORT, CONNECTICUT.

CUT-OFF VALVE FOR STEAM-ENGINES.

Specification of Letters Patent No. 12,507, dated March 13, 1855.

To all whom it may concern:

Be it known that I, NOBLE T. GREENE, of Bridgeport, in the State of Connecticut, have invented certain new and useful Improvements in the Apparatus for Operating the Cut-Off Valves of Steam-Engines and Regulating the Same, of which the following is a full, clear, and exact description, reference being had to the accompanying drawings, 10 making part of this specification, in which—

Figure 1, is a front elevation; and Fig. 2, an end elevation of my improved apparatus.

The same letters indicate like parts in both the figures.

15 In my said invention the valves are connected with, and operated by, rocking levers or their equivalents, by any suitable mode of connection, and these levers are operated in one direction by the closing of the valves, 20 either by their gravity, by weights connected therewith, or any other suitable means, to insure the rapid closing of the ports, and in the opposite directions to open the ports by means of two spring tappets mounted on, or 25 in a sliding bar having a positive longitudinal motion derived from an eccentric or other suitable part of the engine; and the said tappets are free to slide on, or in the said bar, and at right angles to its length, 30 for the purpose of passing by the levers in the return motion, and of being adjusted to any portion of the stroke, and to admit of adjustment to liberate the valves at any portion of the stroke of the piston. And this 35 part of my invention consists in combining with the levers that operate the valves the spring tappets on the sliding bar, when the said tappets are movable on the said sliding bar at right angles to the line of its motion, 40 or nearly so, to permit the return of the tappets after the valves have been closed rapidly by gravity or the equivalent thereof, and preparatory to the reopening of the valves. And my invention also consists in 45 regulating the periods of closing the valves by means of a gage bar which is adjustable by a governor or other means, when combined with the spring tappets to regulate their position and thereby determine the periods of liberating the valves that they may 50 be closed by gravity or other equivalent means, while the periods of opening the valves remain unchanged.

In the accompanying drawings *a, a*, represent two slide valves (for which other valves may be substituted) connected by

rods *b, b*, with the upper arms of two rocking levers *c, c*, mounted on arbors *d, d*, having arms *e, e*, to which are suspended weights *f, f*, to close the valves when the levers *c, c*, 60 are liberated. When the valves are closed, the rock levers are vertical for a horizontal engine, although this position may be varied.

Below the two rock levers is placed a bar *g*, mounted in suitable standards *h, h*, and 65 receiving a positive longitudinal motion from an eccentric *i*, or other suitable part of the engine. And in this bar are two mortises passing through it at right angles to its length and in which are fitted, so as to 70 work therein freely but accurately, two tappets *j, j*, formed with shoulders *k, k*, to determine the limit of their motion downward, and forced upward by a spring *l*, attached to the lower face of the bar and acting by 75 its tension to force the tappets upward and against the lower edge of a gage bar *m*, placed parallel with the line of motion of the tappet bar. This gage bar has a perpendicular stem *n*, fitted to slide in a standard *o*, 80 where it can be held by a set screw or other known means at any point of adjustment required. Or instead of this the stem may be connected with the governor to determine by the velocity of the engine the position of 85 the gage bar, and hence the height to which the tappets may be forced up by the spring which will determine the period of closing the valves.

It will be seen from the foregoing that as 90 the tappet bar moves in the direction of the arrow one of the tappets is brought in contact with the inner face of the lower arm of one of the levers and causes it to turn on its axis and thereby to open the corresponding valve. And while this takes place the other tappet passes under the other rocking lever without moving it, the tappet and lever being rounded so that when they come 95 in contact the tappet will be forced down 100 until it shall have passed by the lever, when the spring forces it up so that on the return motion of the bar this tappet operates the corresponding lever to open its valve, while the other tappet passes under its corresponding lever. Now it will be seen that by the motion of the tappet bar, the two tappets always act upon, and open, the valves at the same period; but that the periods when the tappets shall liberate the rock levers to permit the valves to be closed depends upon the 105 elevation of the tappets,—that is, the lower 110

the tappets are the quicker they will liberate the levers, and vice versa; and therefore by simply elevating or depressing the gage bar the period of closing the valves can be 5 changed while the period of opening them remains the same.

I do not wish to be understood as limiting myself to the special construction and arrangement of the several parts, but to cover 10 all merely formal variations.

What I claim as my invention and desire to secure by Letters Patent is—

1. Combining with the rocking levers, or their equivalents, for operating the valves 15 the spring tappets on the sliding bars, sub-

stantially as described and for the purpose specified.

2. And I also claim in combination with the sliding spring tappets that operate the rock levers, substantially as described, the 20 employment of the gage bar or any equivalent therefor, to regulate the period of closing the valves, whether the said gage bar be regulated by a governor or by other means, as set forth.

NOBLE T. GREENE.
